UNITED STATES PATENT OFFICE.

HENRY ROHWER, OF SEATTLE, WASHINGTON.

MONEY-HANDLING MACHINE.

1,390,587.

Specification of Letters Patent. Patented Sept. 13, 1921.

Application filed June 22, 1917. Serial No. 176,271.

To all whom it may concern:

Be it known that I, HENRY ROHWER, a citizen of the United States, and resident of the city of Seattle, county of King, State of Washington, (whose post-office address is the same place,) have invented certain new and useful Improvements in Money-Handling Machines, of which the following is a specification.

10 My invention relates to money handling machines and particularly to such machines operated by electrical means. The object of my invention is to devise a machine which is simple in operation and mechanically sturdy and compact, and which will be substantially free from error in operation. Certain parts of the machine may be located at one point and other parts at another, and at the same time secure the same operation as if 20 the parts were united mechanically.

My invention will be more thoroughly understood by reference to the following description taken in connection with the accompanying drawings forming a part of this specification, and in which Figure 1 represents a rear elevation of the machine, with the back part of the casing removed.

Fig. 2 represents a section on line 2—2 of Fig. 1.

30 Fig. 3 shows a sectional enlarged view of the clutch and driving mechanism.

Fig. 4 is an enlarged view of the shortage key and mechanism controlled thereby.

Fig. 5 shows a detail of one of the clutch 35 members.

Fig. 6 shows an enlarged view of one of the electromagnets with its plunger and operating means.

Fig. 7 shows another view of the same 40 arrangement as shown in Fig. 6.

Fig. 8 shows a partial view of the device as shown in Figs. 6 and 7, but in a different position.

Fig. 9 shows a plan view of a section of 45 the galley or money rack.

Fig. 10 shows the lower part of a portion of the galley or money rack.

Fig. 11 shows an enlarged view of the correction key and associated parts.

50 Fig. 12 shows a detail.

Fig. 13 shows an enlarged view of two keys, one of which has been operated and one which has not.

Fig. 14 shows an arrangement of the key- 55 board and some of the electrical connections in diagrammatic form.

Referring to Figs. 1 and 2, the machine comprises a base 1 and side frame members 2, and back plate 3. Suitably attached to the base plate 1 at the front of the machine 60 is a keyboard 4. This keyboard is attached to the base plate by screws 5 and to the side plates by means of screws 6. It is evident that this keyboard may be taken off by simply unscrewing the attaching screws. 65 Mounted in the base of the machine is a motor 7 provided with a pulley 8 and belt 9. The belt 9 is provided with an idler 10. The belt 9 runs over a pulley 11 and is rotated in the direction of the arrows shown in Fig. 1. 70 The pulley 11 is mounted on the shaft 12, which shaft is mounted in a bearing 13, shown at the right of Fig. 2 and a similar bearing (not shown) at the other end of the shaft. Mounted on the shaft 12 is a worm- 75 wheel 14, which meshes with a gear 15 mounted on a shaft 16, which shaft is mounted in bearing 17 in the side frame 2 and in the standard 18 attached to the base of the machine, shown more clearly in Fig. 3. Also 80 loosely mounted on the shaft 16 is a gear wheel 19, which meshes with a gear 20 mounted on the shaft 21 extending across the machine and mounted in bearings 22 on the side frame members 2 and also in a bearing 85 23 mounted between the cross pieces 24, which members are supported upon the standard 18, as shown in Figs. 1, 2 and 3. These members are also fastened to the side frame members 2. 90

Mounted on the shaft 21 are gear segments 95 25 suitably fastened on the shaft by means of the screws 26, which screws are arranged so that their outer ends come flush with the surface of the smooth part of the segments. 95 There is one of these gear segments 25 for each stack of coins in the galley or money rack. By reference to Figs. 6 and 7, it will be seen that each of the segments 25 is arranged to operate a plunger 27. The 100 plunger 27 has two racks, one above the shaft 21 and the other below the shaft. During each operation of the machine, the shaft 21 makes one complete revolution. During the first half of the revolution, the 105 gear 25 cooperates with the lower rack 28 to move the plunger 27 to the left to the position shown in Fig. 7, whereas during the second half of the revolution the gear 25 engages the upper rack 29 and moves the 110 plunger 27 to the position shown in Fig. 6. Attached to the plunger 27 is a plate 30 on

one side and on the other side is another plate exactly the same as the plate 30. These plates extend upward in front of the armature 31 of the magnet 32. These setting 5 magnets 32 are the ones diagrammatically illustrated in Fig. 14 as 113 to 123. Between the plates 30 is pivoted a dog 33. Also mounted between the plates 30 and on top of the plunger 27 is a second plunger 34. 10 The plunger 34 has in its right hand end a notch 35, which is cut away at the left at 36 and at the right at 37. There is also a shoulder 38 on the plunger 34. The dog 33 has a tail portion 39 so shaped as to fit the 15 lower part of the slot 35 when in normal position, as shown in Fig. 6. The sides of the slot 35 are so cut away that when the plunger 27 moves to the left, it will carry the plunger 34 by means of the plates 30 through 20 the connection with the dog 33. This condition will exist unless and until the plunger 34 comes in contact with some obstruction, at which time the connection between the two will be broken, and the plunger 27 will 25 continue to move to the left without the plunger 34 as shown in Fig. 7. The plunger 34 is arranged to move into and through the opening 40 in the galley 41. If there is sufficient money 42 in the galley to extend 30 above the lower part of the opening 40, the plunger 34 will come in contact with the coin and will be arrested in its motion to the left, then as the plunger 27 continues to the left, the parts will assume the position shown 35 in Fig. 7. That is, the dog will move out of the slot 35 and ride up the side 36 to the position which is shown. On the movement of the plunger 27 to the right, the shoulder 38 on the plunger 34 will come in 40 contact with the underside of the dog 33 thereby rotating the dog in a clockwise direction around its pivot 43, and at the same time moving the pivot 43 to the right relative to the plunger 34 until the tail 39 of the 45 dog drops into the slot 35 as shown in Fig. 6. When in this position, the plunger 34 is positively driven to the right by the plunger 27. In its course the plunger 34 strikes the armature 31 of the magnet and pushes the 50 same to the right until all of the parts come to the position as shown in Fig. 6, at which time the gear 25 disconnects from the upper rack 29 and the shaft is automatically stopped as will be hereafter explained. The 55 armature of the magnet illustrated in Fig. 6 is therefore shown in its inoperative position, the plates 30 abutting it to place the racks beyond the reach of operative engagement by the gear 25; while the position 60 of the armature in Fig. 7 may be characterized as its setting position, the point to which it has given plunger 27 that preliminary advance which has enabled gear 25 to engage the rack and complete the entire reciprocal motion thereof.

The gear wheel 19, mounted on shaft 16, has rigidly mounted thereon a clutch member 44 shown in detail in Fig. 5. Mounted on the shaft 16 so as to revolve therewith is a clutch member 45. This member is 70 rotatively attached to the shaft 16 by means of a long key and is so arranged that it is slideable along the shaft in a well known manner by means of an arm 46. The arm 46 is rigidly attached to the member 47 which is 75 pivoted at 48. Connected with the arm 47 is a member 49. This member 49 is provided with screw threads at one end and is attached to the member 47 by the double-lock nuts 50. The opening in the member 47 is 80 a little larger than the stem of the member 49 so that a loose fit is provided to permit free operation. The member 49 extends through the standard 18 and pivotally connects with an electric knife blade switch 51, 85 which switch blade is pivoted at 52. Extending through an opening in the member 49 is a member 53 pivoted at 54 in the standard 18. Pivotally connected to the member 54 is a member 55, which in turn is 90 pivoted to the member 56. The member 56 is pivoted at 57 and has an end 58 projecting under the keyboard 4. Arranged in the keyboard is a member 59, which contacts with the end of the member 58. The member 59 is operated by a suitable push key 60, which extends above the top plate of the keyboard 4. The member 59 is held in the position shown in Fig. 2 by means of a coil spring 61. By operating the push key 60 100 the clutch member 45 is put into operative contact with the clutch member 44 and at the same time the knife blade switch 51 is closed to energize the motor to operate the machine. Referring again to the clutch 105 mechanism shown in Fig. 3, the member 45 has spring operated pins 62 held in the position shown in Fig. 3 by means of the spring 63. The member 44 has cammed notches 64 therein as shown in Fig. 5. These 110 notches are arranged to coöperate with the pins 62. Mounted in the member 47 is a pin 65. In the surface of the clutch member 44 are two notches 66, 180° from each other. The pin 65 in the member 47 is arranged to 115 engage one of these notches 66 to stop the gear 19 at a predetermined point. Mounted on the side of the gear 19 are cam surfaces 67. These cam surfaces are engaged by a pin 68 mounted in the member 47. As the 120 gear 19 revolves, one of the cam surfaces 67 engages pin 68 and moves the member 47 together with the clutch member 45 and the member 49 to the right as shown in Fig. 3, thereby disconnecting the clutch member 45 125 from the member 44 and at the same time opening the knife blade switch 51 to stop the motor. This brings the member 47 directly over the clutch member 44 so that the pin 65 engages one of the notches 66 to stop 130

the gear 19 at a predetermined point. It is understood that the shaft 21 makes one revolution for each operation and the gear 20 is one-half the diameter of the gear 19 and consequently the gear 19 makes one-half of one revolution for each operation of the machine.

When it is desired to throw in the clutch the push key 60 is pressed and the member 10 47 moves to the left as shown in Fig. 3, so that the pin 65 is moved out of the plane of the member 44, so that the same may rotate. Mounted on an extended hub of the gear 19 is a disk 69 as shown in Figs. 2 and 3. This 15 disk 69 has two notches 70 therein which are 180° apart. See Figs. 2, 3 and 4. Mounted on the standard 18 is a knife blade switch 71. This switch blade has a projection 72 thereon, which co-operates with the notches 20 70 in the disk 69. The switch blade is pivoted at 73 and has a tail piece 74 thereon. The switch member 71 when closed connects contacts 75 which completes a common circuit to the operating magnets. The 25 switch blade 71 is biased to closing position by means of the spring 76.

The tail piece 74 of the switch blade 71 extends through a slot in the member 77. This member 77 depends from a shaft 78 30 extending across the machine. This shaft is journaled in the side frame members 2. Suitably attached to this shaft 78 is an apron 79. Arranged on the front of the machine is a shortage key 80 having a stem 35 extending through an elongated hole in the member 77. The pin 81 is fastened in this by means of lock nuts 82 on each side of the member 77.

The purpose of the arrangement which 40 was previously described is to automatically open the circuit common to all of the operating magnets as soon as the motor begins to operate, so that the combination set up on the keyboard cannot be changed after the 45 machine is set in operation. This is accomplished by the cam surfaces or notches 70 in the disk 69, mounted on the shaft 16 throwing the knife blade switch 71 out of contact with the contacts 75 as shown in Fig. 2. If, 50 during a cycle of the machine, it happens that the coins in one or more of the stacks corresponding to one of the selected plungers is below a predetermined point, as for instance that shown in Fig. 8, the plunger 55 34, being permitted to pass through the opening 40 in the galley 41, the dog 33 is brought into contact with the apron 79 which tilts the shaft 78 together with the arm 77 into the position shown in Fig. 8. 60 This causes the push-button and its stem 81 to be moved to the left as represented in Fig. 2, so that the tail piece 74 of the knife blade switch 71 is caught in the upper side of the slotted opening in the member 77 65 and the knife blade switch held open, so that

it is impossible to make a further operation of the machine without first pushing in the shortage key 80 so as to release the knife blade switch to close the circuit of the operating magnets. This warning signal may be 70 given before the money is entirely exhausted from the stack and this may take place at any point depending upon the position of the opening 40 in the galley 41.

Mounted in the side frames 2 is a shaft 75 83. Mounted on the shaft 83 is an apron 84. This apron extends a substantial distance from the shaft and as shown in Figs. 2, 6, 7 and 11 is so placed as to contact with the members 30 extending below the plungers 27. Pivotedly attached to the pivoted shaft is a member 85, which in turn is pivoted to a pin 86 which extends through the main frame of the machine and which has on the outer end thereof an error key 87. 85 Mounted on this pin 86 is a compression spring 88. The object of this arrangement is to correct any mistakes which may have been made and which have been discovered before the motor has been started. If such a mistake has occurred after the magnets have been energized the error key 87 will be pushed in, which will rotate the shaft 83 with its apron, which apron will engage the members 30 of all the plungers which have 90 been selected and move them back to their original position as shown in Fig. 11. Normally this position of the shaft 83 is that shown in Figs. 2, 6 and 7.

In Fig. 12, I have shown an arrangement 100 for steadyng the plungers 27 in position. This consists in making small depressions 89 in the top of the plungers and providing a ball 90 forced downwardly by a spring 91. The ball 90 enters the depressions 89 and 105 steadies the plunger. In Fig. 12 it is shown when the plunger is in normal position. The second depression 89 is shown, which is the position the plunger takes when it is actuated by the magnet but before it is 110 moved by the shaft 21.

Referring to Figs. 9 and 10, which represent partial views of the galley, the stacks 92 and 93 take twenty-dollar gold pieces, stacks 94 and 95 take ten-dollar gold pieces, and the stacks 96 and 97 take five-dollar gold pieces. The stack 92 delivers two 20's in 115 each operation of the plunger, whereas the stack 93 delivers only one. The same is true of the stacks 94 and 95 respectively and also of the stacks 96 and 97 respectively. 120

The distance from the bottom 98 of the stack 92 to the apron 99 which extends entirely across the galley, varies with the different stacks. It is this distance which determines the number of pieces that will be ejected by each plunger, as stated above. This permits the coin to drop down so that the plunger 27 in certain of the stacks 125 engages two coins instead of one as it does in 130

certain others all of which is explained below.

In Fig. 13 are shown two keys 100 and 101. The key 101 is shown depressed, whereas the other is in its normal position. Each key comprises a push-button suitably mounted on a stem 102. This stem extends through the plates 103 and 104 which are of insulating material. Located between these plates and around the stem is a spring 105, one end of which rests against the plate 104 and the other end against the sleeve 106. Mounted on the lower end of the stem 102 is a button of conducting material 107. This button contacts with the spring contacts 108 and 109, and the lower end of the stem engages the spring contacts 110, which contacts are connected to the wire forming the common side of the circuit of all electro-magnets. All these contacts are supported by an insulating plate 111, and may be fastened to this plate in any suitable manner. As shown in Fig. 14, the keys may have contacts ranging in number from 1 to 8, not counting the common contacts 110, which contacts are used in all of the keys. Two contacts 110 are used in each case merely for the purpose of preventing transverse strain on the stem 102. In each case, these common contacts are electrically connected together. When the button 107 is in the position of the key 101, both contacts 108 and 109 are electrically connected with the common contact 110. This is true with respect to all of the contacts when there are two, as shown in Fig. 13, or more than two as for instance, as represented by the \$38.91 key, as shown in large figures on Fig. 14. In that case, when the key is pressed, the five contacts shown on the \$38. key are connected with the common side and the five contacts of the 91¢ key are also connected with the common side. Each of the contacts 108 and 109 of Fig. 13 and the other contacts in all other keys are connected with an operating magnet. This electrical diagram is shown in Fig. 14 in connection with the keys representing \$38.91, and the circuits are as follows:

From the positive main through the wire 112 to the common wire 113 connected to one side of all electro-magnets. By reason of the fact that the key 38 is pressed, a circuit is created through the magnets 114, 115, 116, 117 and 118 by bringing the contacts 108 and 109 into contact with the common contacts 110, as shown in Fig. 13. By reason of the fact that the key 91 is pressed, the magnets 119, 120, 121, 122 and 123 are energized for the same reason. This causes the plungers operating on the twenty-dollar, ten-dollar, five-dollar, two one-dollar and two fifty-cent pieces to be placed in operative relation to the gear sectors 25 on the shaft 21. In the 65 cents section of the keyboard the magnets

operating on the stacks or receptacles containing fifty-cent, twenty-five-cent, ten-cent, five-cent and one-cent pieces will be likewise placed in operative condition. After this has been accomplished, the push-button 60 is pressed down which starts the motor and connects the clutch, and which in turn causes one revolution of the shaft 21 and a complete operation of each of the above designated plungers, thereby delivering to the 70 conveyer belt 124 the coins to the value of \$38.91, and which coins are delivered by the belt to the delivery coin spout 125, shown in Fig. 1. Shown in Fig. 1 is a fuse plug 126, having fuses 127 therein. Also a snap 80 switch 128 is shown in the side frame member 2 of the machine for placing the current on the machine.

Referring to Fig. 2 in connection with the push-button 60 are provided two contacts 129, which are adapted to be connected together electrically by the metal button 130 on the stem 59. These contacts complete a circuit through the magnet 131, Figs. 1 and 3 which has an armature 132 mechanically 90 connected to the member 47. If it is desired to operate this part of the machine electrically, the parts 53, 54, 55, 56, 57 and 58 will be eliminated and the member 47 moved by the magnet 131. This arrangement is 95 particularly useful when the keyboard is in one place and the other part of the machine is in another place. When the machine is manufactured these contacts 129 and the magnet 131 are provided extra, so that the 100 machine may be readily converted from mechanical operation to electrical operation without the taking apart of the machine and the adding of any extra parts, as these extra elements in no way interfere with the operation of the machine mechanically. 105

The galley 41 is held in place on the machine by providing on the upper part of the machine and attached to the side frame members 2, a brace member 133. This brace 110 133 has cut therein two notches 134, as shown in Fig. 1. Attached to the back of the galley are two projections 135 in the form of screws or other suitable form, as shown in Fig. 4 and Fig. 9. The lower 115 back part of the galley has a flange 136 integrally attached thereto, which fits into a corresponding groove in the supporting member 137. The galley is also provided with suitable handles 138. The galley may 120 be removed from the machine by taking hold of the handles and lifting it up, whereupon the projections 135 are removed from the slot 134, and likewise the flange 136 is lifted out of its slot and the galley is thereby detached, and may be with its contents, placed in a vault or other suitable place for safe keeping. This conserves space by making it unnecessary to place the whole machine in such place for safe keeping. It is under- 125 130

stood that the galley may be made of any size dependent upon the use to which the machine is adapted and its contents may, under such circumstances, be many thousands of dollars.

The keyboard is usually provided with 210 keys. The hundred on the left, as shown in Fig. 14 represent what may be called the dollar keys, while the hundred on the right 10 of Fig. 14 are the cents keys. The ten keys in the center are change keys and may be wired up so as to give the change in a variety of denominations. The wiring for the five-dollar key and the one-dollar key is shown 15 in dotted lines in Fig. 14, and for simplicity in the drawings, I have not shown the wiring of the other keys, as the wiring may be varied according to the desires of the owner 20 of the machine and will be perfectly apparent from the wiring which I have shown. The wiring of the five-dollar key is as follows: A common contact is connected to the contact of all the other keys. The three remaining contacts are connected respectively 25 to the magnets 11', 10' and 9', thus giving the five dollars change in the form of four one-dollar and two fifty-cent pieces.

The one-dollar key is wired as follows: The contact is connected to the contact of 30 all the other keys. The five remaining contacts are connected respectively to the magnets 8', 7', 6', 5' and 4', thus giving the change in the form of one fifty-cent, one twenty-five cent, two ten-cent and one five-cent piece. It is obvious from this that the 35 various change keys may be wired up so as to give the change in any denominations desired. It is also understood that anyone of the keys shown on the keyboard may be 40 provided with a greater or less number of contacts than that shown in the drawing in Fig. 14. They may likewise be wired up in various ways to produce the coin or change in any form, and it is understood that the 45 showing in Fig. 14 is merely for the purpose of illustration and infinite variations thereof may be made.

The keys are each provided with a suitable button with the indication thereon being 50 representative of the amount of change each key represents. This is a well known feature in keys of this character. The operation of my machine is as follows:

The switch 128 is closed and the keys representing the desired amount are operated, and in the operation of the machine I will 55 describe it as if the keys representing \$38.91 have been operated, and on this assumption the keys representing these figures would be 60 pressed down either at the same time or successively. The key for \$38.00 closes the circuit through the magnets 114, 115, 116, 117 and 118 and the key for 91¢ closes the circuit through the magnets 119, 120, 121, 122, 65 and 123, all as clearly shown in Fig. 14.

This causes all of the magnets, 114 to 123 inclusive, to operate to throw the corresponding plunger 27 to the left so that the first tooth of the lower rack 28 as shown in Fig. 6 will be placed in a position to be engaged by the second tooth of the gear sector 25. The push button 60 is then depressed. This, if operating mechanically, closes the switch 51 in the motor circuit through the members 49, 53, 55, 56 but if operating electrically, closes the contacts 129 and energizes the magnet 131 performing the same function. The movement of the member 49 to the left as shown in Fig. 3 likewise moves the member 47 with its attached arm 46 to the left, removing the pin 65 from the slot 66 in the side of the clutch member 44 and at the same time brings the clutch member 45 to the left, so that the pins 62 engage in the cam slots 64 in the clutch member 44. The apparatus is so arranged that the motor circuit is closed a short time before the clutch member 45 is brought into operation with the member 44, thus allowing time for the motor to speed up. When the motor starts, 70 it revolves the shaft 12 by means of the belt 9, thereby revolving the worm 13, which in turn revolves the worm-wheel 15 of the shaft 16 on which the clutch member 45 is slidably but non-rotatively mounted. The rotation 75 of the clutch member 45 is transmitted to the clutch member 44 and from thence to the gear wheel 19, which is in mesh with the gear 20, causing the shaft 21 to rotate. This 80 apparatus is so arranged that the motor circuit is closed a short time before the clutch member 45 is brought into operation with the member 44, thus allowing time for the motor to speed up. When the motor starts, 85 it revolves the shaft 12 by means of the belt 9, thereby revolving the worm 13, which in turn revolves the worm-wheel 15 of the shaft 16 on which the clutch member 45 is slidably but non-rotatively mounted. The rotation 90 of the clutch member 45 is transmitted to the clutch member 44 and from thence to the gear wheel 19, which is in mesh with the gear 20, causing the shaft 21 to rotate. This 95 apparatus is so arranged that the motor circuit is closed a short time before the clutch member 45 is brought into operation with the member 44, thus allowing time for the motor to speed up. When the motor starts, 100 it revolves the shaft 12 by means of the belt 9, thereby revolving the worm 13, which in turn revolves the worm-wheel 15 of the shaft 16 on which the clutch member 45 is slidably but non-rotatively mounted. The rotation 105 of the clutch member 45 is transmitted to the clutch member 44 and from thence to the gear wheel 19, which is in mesh with the gear 20, causing the shaft 21 to rotate. This 110 apparatus is so arranged that the motor circuit is closed a short time before the clutch member 45 is brought into operation with the member 44, thus allowing time for the motor to speed up. When the motor starts, 115 it revolves the shaft 12 by means of the belt 9, thereby revolving the worm 13, which in turn revolves the worm-wheel 15 of the shaft 16 on which the clutch member 45 is slidably but non-rotatively mounted. The rotation 120 of the clutch member 45 is transmitted to the clutch member 44 and from thence to the gear wheel 19, which is in mesh with the gear 20, causing the shaft 21 to rotate. This 125 apparatus is so arranged that the motor circuit is closed a short time before the clutch member 45 is brought into operation with the member 44, thus allowing time for the motor to speed up. During the second half of the revolution of the shaft 21, the gear sectors engage the teeth of the upper rack 29 as shown in Fig. 7 and move the plungers 27 back to their original position, as shown in Fig. 6. The backward 130

movement of the plungers 27 carries the magnet armature back to its original position by means of the plates 30 engaging the lower part of the armature. Soon after the 5 motor starts and the clutch takes hold, the switch 71 is thrown out of engagement with the contact 75 and opens the common circuit of the keys on the keyboard. This throws the tail part 74 down and the switch 10 71 rides up out of notch 70 as the motor starts on to disk 69 and is thus opened. When the money in one of the stacks is below the opening 40, the plungers 34, which 15 normally go forward with the plunger 27 passes through the opening so that the dog 33 rocks the arm 78 in a clockwise direction throwing the end 77 thereof out so as to prevent the normal closure of the switch 71. If the money is not below the opening 20 40 in any of the stacks, the member 77 will not be thrown to the left, and immediately upon the gear 19 reaching a point 180° from its starting point, the switch will be again automatically closed by the spring 76. If 25 the member 77 has been moved to the left, as above indicated, the same may be moved back by the shortage key 80, as shown in Fig. 2, whereupon the switch 71 will be closed as soon as the cam disk 69 has made 30 one-half a revolution.

In the event that the wrong key has been pressed and the mistake has been discovered before the push-button 60 is pressed, the correction may be made by pressing the 35 push-button 87, as shown in Fig. 11, thus rotating the shaft 83 to the right and bringing the apron 84 into contact with all of the plungers 27, which have been set forward on the previous set-up, thereby pushing 40 the plungers back into their original inoperative position. The desired keys may then be pressed and the operation proceeded with.

While I have described the foregoing 45 machine somewhat in detail, it is understood, of course, that I am not by any means limited to the exact details as described. Neither do I desire to be limited to the exact 50 number of keys shown on the keyboard nor to the number of receptacles in the galley nor the particular arrangement of the receptacles in the galley, because, if it is desired to make a machine larger than that shown, the same can be constructed by 55 merely duplicating the parts shown and widening out the machine, as well as by increasing the length of the receptacles in the galley. The making of these changes is perfectly obvious and merely entails the 60 duplication of the parts as described.

Having described my invention, what I claim as new and desire to secure by Letters Patent, is:—

1. In a machine of the character described, 65 the combination of a plurality of receptacles

for coins, a plunger for ejecting one or more coins from each receptacle, means for selectively operating each of said plungers comprising a double rack, a gear sector for engaging said racks and means for bringing 70 said racks into engagement with the gear sector and means for operating said gear sector.

2. In a machine of the character described, the combination of a plurality of receptacles 75 for coins, a plunger for ejecting one or more coins from each receptacle, means for selectively operating each of said plungers comprising an upper and lower rack, a shaft, a gear sector on said shaft for each plunger, an 80 electro-magnet for causing each rack to engage its sector and means for revolving said shaft one revolution to thereby move the racks forward and back to their original position. 85

3. In a machine of the character described, the combination of a plurality of keys, a circuit common to a plurality of said keys, a switch in said circuit, a plurality of coin receptacles, plungers therefor, a motor for operating said plungers, a circuit for said motor, a switch in said circuit, means for closing said motor switch and means operated by the motor for opening said first switch immediately after the motor starts. 95

4. In a machine of the character described, the combination of a plurality of keys, a circuit common to a plurality of said keys, a switch in said circuit, a plurality of said keys, a switch in said circuit, a plurality of coin receptacles, plungers therefor, a motor for operating said plungers, a circuit for said motor, a switch in said circuit, means for closing said motor switch, means operated by the motor for opening said first switch immediately after the motor starts and means for automatically opening said motor circuit upon the completion of one cycle of operation of said plungers. 105

5. In a machine of the character described, 110 the combination of a plurality of keys, a circuit common to a plurality of said keys, a switch in said circuit, a plurality of coin receptacles, plungers therefor, a motor for operating said plungers, a circuit for said 115 motor, a switch in said circuit, means for closing said motor switch, means operated by the motor for opening said first switch soon after the motor starts and means preventing the closing of said first switch, if the coin in any of said receptacles is below a predetermined point. 120

6. In a machine of the character described, the combination of a plurality of keys, a circuit common to a plurality of said keys, 125 a switch in said circuit, a plurality of coin receptacles, plungers therefor, a motor for operating said plungers, a circuit for said motor, a switch in said circuit, means for closing said motor switch, means operated by 130

the motor for opening said first switch soon after the motor starts and means for automatically opening said motor circuit, and means preventing the closing of said first switch, if the coin in any of said receptacles is below a predetermined point.

7. In a machine of the character described, the combination of a plurality of keys, a circuit common to a plurality of said keys, a 10 switch in said circuit, a plurality of coin receptacles, plungers therefor, a motor for operating said plungers, a circuit for said motor, a switch in said circuit, means for closing said motor switch, means operated by the motor for opening said first switch soon after the motor starts, means for automatically opening said motor circuit, means preventing the closing of said first switch, if the coin in any of said receptacles is below a 15 predetermined point, and means rendering said last means ineffective.

8. In a machine of the character described, the combination of a plurality of keys, a circuit common to a plurality of said keys, a 20 switch in said circuit, a plurality of coin receptacles, plungers therefor, a motor for operating said plungers, a circuit for said motor, a switch in said circuit, means for closing said motor switch, means operated by the motor for opening said first switch soon after the motor starts, means preventing the closing of said first switch, if the coin in any of said receptacles is below a predetermined point, and means rendering said last 25 means ineffective.

9. In a machine of the character described, the combination of a plurality of keys, magnets responsive to said keys, plungers set in operative position by said magnets, a motor, 30 a switch in the motor circuit, a shaft for operating said plungers, a clutch for operating said shaft, means for closing said switch and throwing in said clutch and means automatically stopping said motor 35 and throwing out said clutch upon the completion of one cycle of operation of said plungers.

10. In a machine of the character described, the combination of a plurality of keys, magnets operated by said keys, plungers operated to preparatory position by said magnets and means for moving said operated plungers back directly to their original position without their performing a normal cycle.

50 11. In a machine of the character described, the combination of a plurality of plungers, means for operating said plungers, means for operatively moving said racks and pinions into engaging position, means for selectively operating said first means and means for simultaneously placing said plungers in inoperative condition.

55 12. In a machine of the character described, the combination of a shaft, a plurality of gear sectors mounted thereon, a plunger operated by each of said sectors, said plungers being normally disconnected from said sectors and means selectively placing said plungers and sectors in operative relation.

60 13. In a machine of the character described, the combination of a shaft, a plurality of receptacles for containing coins, a plurality of gear sectors on said shaft, means coöperating with said sectors for ejecting coins from said receptacles but normally disconnected therefrom, electro-magnets operating when energized to selectively place said means in operative relation to said sectors and means for operating said shaft.

65 14. In a machine of the character described, the combination of a plurality of keys, a plurality of magnets operated by said keys, circuits for said magnets, a plurality of receptacles for coins, a motor, a plurality of plungers operated by said motor for ejecting coins from said receptacles, and means for opening the circuits of said magnets before said plungers are effective to eject 70 80 90 coins from said receptacles.

In testimony whereof, I have signed my name to this specification.

HENRY ROHWER

It is hereby certified that in Letters Patent No. 1,390,587, granted September 13, 1921, upon the application of Henry Rohwer, of Seattle, Washington, for an improvement in "Money-Handling Machines," an error appears in the printed specification requiring correction as follows: Page 7, line 58, claim 11, after the word "plungers" and before the comma, second occurrence, insert the words *through rack and pinion*; and that the said Letters Patent should be read with this correction therein that the same may conform to the record of the case in the Patent Office.

Signed and sealed this 18th day of October, A. D., 1921.

[SEAL.]

KARL FENNING,

Acting Commissioner of Patents.
